UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

REFRIGERATOR.

Application filed June 18, 1925, Serial No. 37,971. Renewed July 14, 1927.

This invention relates to refrigerators or cabinets, and has for its object a construction of an insulated refrigerator or cabinet which is relatively light in weight and has 5 all the advantages of stone surfaces. In my Patent No. 1,538,469, issued May 19, 1925, I have described and claimed a double shell stone refrigerator. This makes a very efficient and beautiful piece of furniture, but it has the disadvantage of being 10 relatively heavy and rather easy fractured in transit. Furthermore, this type of refrigerator can only be made by casting operations and these require considerable time in 15 setting and involve a large investment in moulds where production assumes any proportions. It is the object of the present invention to provide a design of refrigerator or cabinet which is relatively light but has 20 relatively great strength to withstand rough handling and yet it is finished in stone inside and out, and all the joints are hermetically and forever sealed by stone. This sealing of the joints is, however, a very great 25 improvement over the ordinary wooden or painted and varnished refrigerator, as such a refrigerator inevitably breaks down by moisture getting into the joints and causing swelling or the wood drying out and the 30 joints pulling apart by shrinkage. In my refrigerator, the joints are entirely eliminated, obviating not only the self-destruction of the box in time but of avoiding the unsanitary condition which always attends 35 open joints.

The box is preferably a white stone inside and out without any metal framework, as is necessary with the ordinary porcelain refrigerator in which porcelain is used on the 40 outside. Furthermore, the refrigerator may be made in colors by introducing any suitable coloring material or pigment into the stone mix. Another advantage in this refrigerator is its economical construction, for 45 in large production it is cheaper to construct a refrigerator such as I am about to describe than to manufacture the ordinary wood finished box, for the wood work in my refrigerator is comparatively a rough box or crate-like job which can be put together by rough carpentry, whereas the ordinary wooden box 50 is more or less a cabinetmaker's job.

Referring to the drawings:

Fig. 1 is a perspective view of the completed refrigerator, but without the doors in 55 place.

Fig. 2 is a perspective view of the completed wooden set up or core.

Fig. 3 is a perspective view of the outer core of wood. 60

Fig. 4 is a perspective view of the inner core of wood.

Fig. 5 is a horizontal cross section of the moulds before the casting is poured.

Fig. 6 is a similar view showing the casting 65 poured, the insulating material in place and the back nailed on.

Fig. 7 is a perspective view of a modified form of outer core refrigerator.

Fig. 8 is a perspective view of the refrigerator front. 70

Preferably I form an inner wooden box or crate *a*, this can be made out of rough wood, and is preferably California redwood. This crate is divided off into the ice chamber 75 *b* and the provision chamber *c*, but of course may be divided in any other way. The side walls extend beyond the top and bottom walls to form tracks *d* and *e* adapted to ride in the grooves *f* and *g* respectively to the 80 outer box which is designated *h*.

The inner shell is slipped into the outer shell, preferably from the front, although it may be slipped in from the back, where an outer case such as shown in Fig. 7 is 85 used, having grooves which extend entirely through from the front to the back. The wooden front frame shown in Fig. 8 and designated *j* is then nailed to the two wooden boxes and this completes the wooden inner 90 set up. This entire wooden set up may then be inserted in suitable moulding dies, as shown in Fig. 5. These comprise the moulds *k* and the cores *m*. Obviously the cores for the passageways (these are not shown) will 95 have to be withdrawable into the other core members or separable therefrom to permit the withdrawal of the cores after the stone is set.

The stone is preferably what is known as 100 oxy-chloride, being a stone mix made up of preferably 20% magnesium oxide by weight, 30% of finely ground silica by weight, and 50% of 50 mesh silica sand by weight. To

this dry mix is added sufficient magnesium chloride in solution at 26 Baumé density to form a mix that will easily pour. I find this a very suitable casting mix. This method of 5 making a refrigerator or cabinet is in its general aspects described and claimed in my application filed January 31, 1925, No. 6,023.

However, in the aforesaid application, the 10 final product is not claimed and this final product may be made in several ways, as for instance, the stone coated wooden core shells may be separately cast or manufactured and then put together afterwards in much the 15 same way as described in the two patents that I have first referred to. Or on the other hand, a very desirable way of manufacturing the refrigerator or cabinet here shown and claimed is to use a spray for coating the 20 wood. Both the inside and the outside may be sprayed with the oxy-chloride cement, or preferably the inside shell will have a coating moulded in, while the outside shell will have to be sprayed. The boxes may be even 25 dipped in a suitable mixture. I have found that for spraying it is preferable to use a mixture that is more adapted for the spraying gun. I have found, for instance, that a mixture of 25% by weight of magnesium 30 oxide, 50% of ground silica and 25% of lithopone mixed with a solution of magnesium chloride at 26 Baumé density to produce a relatively thin mixture that can be handled in a spraying nozzle will work admirably. 35

I have discovered that this plastic material has most unusual cooperation with the wood—something that does not happen with ordinary enamels, paints, or lacquers. This 40 mix has a considerable magnesium chloride and any of the saline compositions or materials, such as common salt, (sodium chloride) and calcium chloride have a great affinity for moisture. I find that the magnesium chloride soaks into the wood and tends to keep it moist. This prevents any shrinking and on the other hand makes the joints swell and fit tightly together. There 45 is no tendency for them ever to draw apart and break the stone coating, as is common with an ordinary varnished box. This action, I take it, is due to the use of magnesium chloride and I customarily brush magnesium chloride solution onto the box 50 first before I spray it, and this may also be done either in the dipping or casting process. This insures the magnesium chloride with its affinity for moisture soaking into the wood where it remains permanently in 55 the same way that calcium chloride will keep the dust down permanently on a road where it has been strewn.

Another thing that I find useful in this 60 type of box over a solid stone refrigerator is that the wood core makes a suitable an-

choring medium for the usual hardware 70 hinges and locks that have to be secured to the front of the refrigerator. In my prior stone casings I was obliged to use special bushings for this purpose.

With the present construction, suitable 75 places may be left by contacting of the mould parts with the wooden core or by removal of spots of the material if spraying or dipping is used. Preferably too, it is desirable 80 to leave the wood exposed along the heavy line designated *n* in Figs. 1 and 6. This may be accomplished by lips on the dies for contacting with the wooden core and preventing the thin coat from setting over the 85 core at the door openings. This breaks the continuity of the composition stone outside and in, and consequently arrests the heat conductivity of the stone coating and prevents undesirable abstraction of heat from 90 the exterior.

The space between the outer wooden shell and the inner wooden box is filled with an insulating material which is designated *w*, 95 which may be, for instance, ground cork and pitch. Preferably a metal back plate *y* is nailed to the wooden strips *s* which are held in the pitch and is also nailed to the projecting portion of the wooden outer box, the back plate being provided with turned 95 up flanges *t* for this purpose.

Preferably I coat the outside and inside 100 with some form of pyroxylin enamel, such as "Dues" a well known preparation made by E. I. Du Pont De Nemours Co. of Wilmington, Del.

What I claim is:

1. A refrigerator or cabinet, comprising a box-like core of fibrous material encased on the outside and inside by artificial stone coating, there being an omission of the coating and an exposure of the wooden core at a point where the inner coat and the outer coat would otherwise meet. 105

2. A refrigerator or cabinet, comprising a unit double box structure forming a core of fibrous material and a plastically applied artificial stone coating encasing both the inside and the outside of the said structure, the space between the two box-like walls of the core being packed with insulating material. 110

3. A refrigerator or cabinet, comprising a wooden outer box, a wooden inner box provided with projecting sides adapted to support the inner box and the outer box in spaced relation, and plastically applied artificial stonework enveloping the outside of the outer box and the inside of the inner box as a unit. 115

4. A refrigerator or cabinet, comprising a wooden outer box, a wooden inner box spaced from the outer box, and held in assembled relation therewith by means of grooves, and a stone coating on the exposed surface of one of the wooden boxes. 125

5. A refrigerator or cabinet, comprising a wooden outer box, a wooden inner box spaced from the outer box, and two stone coatings formed by a single casting operation on the exposed surfaces of the two boxes.
6. A refrigerator or cabinet, comprising a wooden outer box, a wooden inner box spaced from the outer box, and the exposed surfaces of the two boxes being coated with stone and the space between the two boxes suitably insulated, the continuity of said stone coating being broken at certain points to arrest the heat conducted thereof.
- 10 7. A refrigerator or cabinet, comprising an outer box and an inner box, one of said boxes provided with grooves and the other with tracks arranged to ride in said grooves to space the two boxes with respect to each other, and a plastically applied stone coating on the exposed surface of one of said
- 15 boxes, and the space between the two boxes being packed with insulating material.
8. A refrigerator or cabinet, comprising an outer box provided with grooves, an inner box provided with tracks arranged to ride in said grooves to properly position the inner box within the outer box in spaced relation therewith and, a plastically applied stone coating on the exposed surface of one of said boxes.
- 20 9. A refrigerator, or cabinet, comprising a unit core formed of a double box structure of fibrous material, and plastically applied artificial stone coating encasing both the inside and outside of said unit core, the continuity of said stone coating being broken to arrest the heat of conductivity between said inside and outside coatings.

In testimony whereof I have affixed my signature.

LLOYD G. COPEMAN.
